UNITED STATES PATENT OFFICE.

RUDOLPH DRESSLER, OF NEW YORK, N. Y., ASSIGNOR OF ONE-THIRD TO
ANDREW J. HOLM, OF BROOKLYN, NEW YORK.

CORK-PULLER.

SPECIFICATION forming part of Letters Patent No. 730,007, dated June 2, 1903.

Application filed August 30, 1902. Serial No. 121,558. (No model.)

To all whom it may concern:

Be it known that I, RUDOLPH DRESSLER, a citizen of the United States, residing in New York, borough of Kings, and State of New York, have invented certain new and useful Improvements in Cork-Pullers, of which the following is a specification.

This invention relates to certain improvements in cork-pullers of that class by which the cork is lifted bodily from the mouth of the bottle by means of spurs that are forced into the body of the cork after the pointed shank of the device has been forced to a certain depth into the cork; and for this purpose the invention consists of a cork-puller consisting of a head, a tubular shank connected therewith and having diametrically opposite slots arranged in groups one above the other in planes at right angles, a pointed tip on the end of said shank, a movable rod arranged in said shank having transverse slots registering with said diametrically opposite slots, oppositely-disposed spurs carried in the slots of said rod adapted to advance and recede in the slots of the shank upon movement of said rod, levers fulcrumed in said head projecting from opposite sides thereof, means connecting said levers with said rod, and a spring in said head controlling said levers, rod, and spurs, as will be more fully described herein-after and fully pointed out in the claims.

In the accompanying drawings, Figure 1 represents a side elevation of my improved cork-puller, showing the parts in their normal positions. Fig. 2 is a side elevation of the same, showing the cork-puller inserted into a cork and the parts in position for withdrawing the same from the bottle. Fig. 3 is a side elevation of Fig. 1. Fig. 4 is a side elevation with one-half of the head and shank of the cork-puller removed, so as to show the interior construction. Figs. 5 and 6 are details of the operative parts of the cork-puller, drawn on a larger scale; and Figs. 7 and 8 are horizontal sections, respectively, on lines 7, 7, Fig. 5, and 8, 8, Fig. 6.

Similar letters of reference indicate corresponding parts.

Referring to the drawings, A represents the shank, B the head, and C the tapering point of my improved cork-puller. The head and

shank are made of two semisections, which are preferably stamped from sheet metal by means of suitable dies, the shank portion being made semicircular in cross-section, while the head is made of flat and approximately oval shape in front elevation. The semisections are provided with abutting edges and connected by one or more fastening-screws b, that pass through the head portion of the sections, and by a tapering point C, which is provided with an interiorly-threaded socket c, that engages the screw-threaded lower ends a of the shank-sections, as shown clearly in Figs. 4, 5, and 6. The shank is thus tubular in form, so as to guide a connecting-rod D, preferably of round cross-section, the lower end of which is provided with transverse recesses d, arranged in planes at right angles to each other and one above the other. In each recess is pivoted a pair of oppositely-projecting spurs D', which pass through corresponding recesses d' in the shank A to the outside of the same or which are folded away in said recesses d when actuated by means of levers E, which latter are fulcrumed at their inner ends in the head B of the cork-puller and connected by pivot-links e with the upper end of the connecting-rod D, as shown clearly in Fig. 4. A helical spring f is interposed between the shoulders f' of the head and the lower ends of the pivot-links e, so that normally the levers E by the tension of the helical spring f are in a position sidewise of the head B, as shown in Fig. 1, while simultaneously the spurs are in a position withdrawn into the recesses of the shank, as shown clearly in Fig. 5. The arrangement of the helical spring f causes the actuating-levers E, the rod D, and the spurs to be moved simultaneously, and by means of the pivot-link connection between the levers E and the connecting-rod D both levers are operated simultaneously whether one or the other is operated.

The operation of my improved cork-puller is as follows: The cork-puller is taken hold of between the fingers by placing the head of the same in the palm of the hand and the middle fingers below the outwardly-curved ends of the levers E. The tapering point C is then, together with the shank B, forcibly inserted into the cork to be pulled to suffi-

cient depth so that the cork extends sufficiently above the uppermost pair of spurs *b*. Pressure is next exerted by the middle fingers on the lower ends of the levers *E*, so that 5 they are spread apart, causing the depression of the rod *D*, which produces the simultaneous outward motion of the spurs into position shown in Figs. 4 and 6, whereby both pairs of spurs extend in planes at right angles 10 with each other and are embedded into the body of the cork, so that by an upward pull on the levers *E* the cork can be readily withdrawn from the mouth of the bottle. By then moving the levers down to the sides of the 15 head of the cork-puller the rod *D* is retracted and the spurs are drawn back into the shank of the cork-puller, so that the cork can be readily taken from the shank.

I am aware that cork-pullers based on the 20 same principle have been patented heretofore; but I am unaware that a cork-puller was ever before used in which the actuating-levers upon being acted upon by the fingers forced the laterally-extending spurs into the 25 body of the cork, so that by a continuous pulling motion on the levers in upward direction the cork was withdrawn from the mouth of the bottle. This continuity of motion produced by the fingers on the actuating-levers *E* constitutes the essential advantage of my improved cork-puller. Another feature is that by the return motion of 30 the levers into their normal position alongside of the head of the cork-puller the spurs are drawn back into the shank, so that the shank can be readily withdrawn from the cork without injuring the same to any great extent, so that the cork can be used over again, if desired, it being not split up or injured, as is 35 40 the case with corkscrews and other cork-pulling devices.

Having thus described my invention, I claim as new and desire to secure by Letters Patent—

45 1. A cork-puller, consisting of a head, a tubular shank connected therewith and having diametrically opposite slots arranged in groups one above the other in planes at right angles, a pointed tip on the end of said shank, 50 a movable rod arranged in said shank having

transverse slots registering with said diametrically opposite slots, oppositely-disposed spurs carried in the slots of said rod adapted to advance and recede in the slots of the shank upon movement of said rod, levers fulcrumed 55 in said head projecting from opposite sides thereof, means connecting said levers with said rod, and a spring in said head controlling said levers, rod and spurs, substantially as set forth. 60

2. A cork-puller, consisting of a head, a tubular shank formed integral therewith and having diametrically opposite slots arranged in groups in planes at right angles, said head having an opening extending transversely 65 thereof and in communication with the hollow of the shank, a movable rod, a plurality of spurs carried on said rod adapted to advance and recede in the slots of said shank, oppositely-disposed levers fulcrumed in said head 70 at opposite ends of the opening thereof, links connecting said levers with said movable rod, and a spring on said rod for normally retaining said spurs in receded position and the levers in folded depending position, substantially as set forth. 75

3. A cork-puller, consisting of two separably-connected semisections forming a tubular shank and a hollow head, a pointed tip at the end of said shank, a movable rod arranged 80 in said tubular shank, said rod and shank having diametrically opposite slots arranged in planes at right angles and one above another, spurs pivotally projecting from the slots of said rod and adapted to advance and 85 recede in the slots of said shanks upon movement of said rod, levers fulcrumed in the hollow head at opposite sides, links connecting said levers with said rod, a compression-spring in said head arranged on said rod for 90 controlling said rod, levers and spurs, substantially as set forth.

In testimony that I claim the foregoing as my invention I have signed my name in presence of two subscribing witnesses.

RUDOLPH DRESSLER.
